UNITED STATES PATENT OFFICE.

SIMON BUSCAVAGE, OF SHENANDOAH, PENNSYLVANIA.

DESIGN FOR A SACRAMENTAL SHRINE.

55,590.

Specification for Design.

Patented July 6, 1920.

Application filed December 11, 1919. Serial No. 344,150. Term of patent 3½ years.

To all whom it may concern:

Be it known that I, SIMON BUSCAVAGE, a citizen of Lithuania, and a resident of Shenandoah, in the county of Schuylkill and State of Pennsylvania, have invented a new, original, and ornamental Design for a Sacramental Shrine, of which the following is a specification, reference being had to

the accompanying drawings, forming part thereof.

The figure is a front view of a sacramental shrine showing my new design.

I claim—

The ornamental design for a sacramental shrine as shown.

SIMON BUSCAVAGE.
